FLUID HEATER

George I. Carter, Longmeadow, Mass.

Application February 19, 1948, Serial No. 9,410

4 Claims. (Cl. 122—137)

1

The present invention relates generally to fluid heaters and vaporizers, and more particularly to fluid heaters and vaporizers of the horizontal fire tube type.

The present invention has particular utility in a steam generator adapted to be fired with gas or oil and will be more particularly described in connection with such use. However, it is to be understood that the invention is equally applicable and efficient for use as an air heating device.

It is an aim of the present invention to provide a fluid heater and vaporizer which will operate with improved efficiency so that a greater amount of heat may be derived from the hot combustion gases without increasing the size of the device. In connection with this aim, it is an object to provide a fluid heater and vaporizer which is characterized by a relatively small and compact design in relationship to output.

A further aim of the invention is to provide a fluid heater and vaporizer which is of simplified construction and, therefore, easy to fabricate and assemble. Included in this aim is the elimination of expensive, unnecessary or complicated parts and the provision of a fluid heater and vaporizer which may be manufactured at a cost at least comparable to that of less efficient devices.

A further object of the invention is to provide a fluid heater and vaporizer which is of rugged construction and foolproof in operation and assembly so that satisfactory service over long periods of time may be reasonably expected.

It is also an aim of the invention to provide a fluid heater and vaporizer which is pleasing in appearance and which is adapted for installation in any desired conventional manner.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings—

Figure 1 is a perspective view of the assembled fluid heater and vaporizer;

Fig. 2 is a cross sectional view at the front end of the device with the front plate removed;

Fig. 3 is a side view partially in cross section

along the line 3—3 of Fig. 2 with the device charged with water; and

Fig. 4 is an end view similar to Fig. 3 with the cross sectional portion taken along the line 4—4 of Fig. 3.

Referring to the drawings in detail, the general appearance of the completed fluid heater and vaporizer of the present invention is best shown in perspective in Fig. 1. As will be noted, 10 the enclosed portions of the device are generally in the shape of an inverted L. The lower leg of the L shaped casing, as denoted by the reference letter A, is the fire box of the device; the horizontal leg of the casing denoted generally by the reference letter B is the heat interchanging section 15 where heat is transferred from the hot combustion gases to the fluid to be heated; and the rear box like portion generally denoted by the reference letter C is a conventional smoke box for leading the hot combustion gases to exhaust.

Referring first to the fire box section A, it will be noted that the same is generally box-like in outline and in the specific embodiment shown the fire box is lined with suitable refractory material

25 10. The actual design of the fire box A forms no part of the present invention and the same may be suitably modified as desired. For example, in some cases it may be preferred to utilize fire box A of the wet base type instead of the dry base type 30 as shown in the specific embodiment in the drawings. The front plate 11 which encloses the front end of the device is provided with a circular opening 12 for receiving an oil or gas burner (not shown) in the usual conventional manner. It is 35 contemplated that the device of the present invention may be used with any standard type of oil or gas burner and the particular burner selected is immaterial insofar as the present invention is concerned.

40 In the specific embodiment shown in the drawings, the fire box A extends slightly less than half of the depth of the device, that is, from front to back. The relative dimensions of the fire box A and the heat interchanging section B are a 45 matter of design and the relative lengths thereof may be varied over a wide range depending upon the desired characteristics of the device. In general, a more efficient operation will be obtained when the heat interchanging section B is relatively long with respect to the fire box A.

The heat interchanging section B to which the present invention is particularly directed is generally rectangular in outline and is located along the top of the fire box A and continues rearwardly therefrom and is supported at the rear by frame members 13. Interior of section B there is disposed a plurality of inclined plates 20, adjacent plates being reversely inclined, which are secured together at their adjacent edges to form a series of wedge-shaped cavities or indentations and dividing the section B into an upper fluid compartment and a lower combustion gas compartment. As best shown in Fig. 4, the wedge-shaped cavities communicating with the upper portion of section B and which are denoted by reference numerals 21, these being V-shaped in cross section, are adapted to contain the fluid to be heated, in the specific embodiment, this being water. The wedges communicating with the lower part of the section B, having a cross section in the form of an inverted V, and which are generally denoted by reference numerals 22, are adapted for the passage of the hot combustion gases from the fire box A. For convenience, these passageways will be referred to more particularly hereinafter as the fire tubes. The inclined arrangement of the plates 20 insures a maximum heat interchanging surface between the hot combustion gases and the fluid to be heated. It also provides the greatest heat interchange where the gases are the hottest and the water is the coldest.

The inclined plates 20 extend from front to rear of the device with the fire tubes or channels 22 being open at the bottom at the front end to the fire box A. The rear portions of the fire tubes or channels 22 are closed at the bottom by the horizontal plate 23 extending rearwardly from the top of the fire box A. The plates 20 are secured at their rear edges to the rear plate 24 in any suitable manner, this rear plate 24 having V-shaped notches 25 cut therein for the egress of the combustion gases into the smoke box C which collects the gases for exhaust through the opening 26 in the usual manner. The rear plate 24 serves as the rear closure for the fluid compartment.

The inclined plates 20 do not extend entirely to the top of the device but have their upper joined edges spaced from the top plate 27 so as to provide a heated vapor collecting space thereabove. As previously mentioned, the specific embodiment is shown for use as a steam generator and in such case the preferred water level or line is somewhat below the top plate 27 but above the upper edges of the plates 20. Suitable openings 28 are provided for the attachment thereto of a suitable sight gauge for indicating the water level. The openings 29 in the top plate 27 are adapted for taking off the heated vapor. The opening 30 in the front plate 11 is a water return or filler opening.

A principal advantage and the novelty of the construction of the present invention lies in the manner in which the front ends of the fire tubes or channels 22 are closed so as to provide heat interchanging surfaces of improved efficiency to provide additional fluid capacity and improved fluid flow while at the same time eliminating any of the usual complicated header arrangements. As best shown in Figs. 2 and 3, the front of the fire tubes or channels 22 are closed by inverted V-shaped plates 31 which are joined to the forward edges of the inclined plates 20. The inclined plates 20 are terminated at the forward end of the device in an incline extending rear-

wardly from the front and bottom of the heat interchanging section B and, accordingly, the V-shaped plates 31 are also inclined rearwardly from the vertical. This inclined positioning of the V-shaped plates 31 provides heat interchanging surfaces at a place where they will be impinged against by the hot combustion gases at the highest temperature and it also provides an additional reservoir section for the fluid to be heated and insures an adequate circulation of fresh water to the wedges 21 so that vapor locks are avoided, all this being accomplished without the need for any complicated header arrangement. As a result of this construction, the efficiency of the device is greatly increased and it is possible to obtain a greater heat interchange with a device of relatively small size.

As will be appreciated, the construction of the present invention is not difficult to fabricate and assemble and there is no arrangement which would tend to develop trouble during service over long periods of time. As a result, it is possible to produce a more efficient and compact fluid heater and vaporizer without increased cost and without the use of complicated or expensive parts.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

40 I claim as my invention:

1. In a fluid heater having a source of hot combustion gases, a series of horizontal fire tubes for permitting passage of said gases to exhaust and providing a heat interchanging surface between the gases and the fluid to be heated, said fire tubes comprising a series of alternately inclined plates joined together along adjacent edges and extending rearwardly from the top of said source, said plates having forward edges which are inclined upwardly and rearwardly and which are closed by similarly rearwardly inclined triangularly shaped plates registering with and connected to said forward edges.

2. In a fluid heater, a series of horizontal fire tubes of generally triangular cross section open at one end to exhaust and means for closing the other end of said fire tubes comprising heat transfer surfaces inclined upwardly and toward said one end.

3. In a fluid heater, a heat transfer section, means in said section forming an upper compartment for fluid to be heated and a series of lower passageways for hot combustion gases, said means comprising a series of alternately inclined plates joined along adjacent edges and extending from front to rear of the section, and means for closing the forward ends of said passageways and forming a fluid reservoir communicating with said compartment, said means comprising upwardly and rearwardly inclined triangularly shaped closure plates secured at their edges to said first named plates.

4. In a fluid heater having a fire box and a heat interchanging compartment extending rearwardly from the top of the fire box, the combination

therewith of a corrugated separator extending lengthwise of the compartment for dividing the compartment into a series of wedge shaped fire tubes below the separator and a series of wedge shaped fluid containers above the separator, said fire tubes being closed adjacent the forward end of the fire box by upwardly and rearwardly inclined members forming a fluid reservoir at the front of the heater and communicating with said fluid wedges, said reservoir narrowing downwardly in longitudinal vertical cross-section, and said compartment extending above the level of said wedges.

GEORGE I. CARTER.
